UNITED STATES PATENT OFFICE

MARCUS C. HOPKINS, OF WASHINGTON, DISTRICT OF COLUMBIA, ASSIGNOR TO HOPKINS CORPORATION, OF JERSEY CITY, NEW JERSEY, A CORPORATION OF DELAWARE

LOUD-SPEAKER

Application filed January 5, 1926, Serial No. 79,829. Renewed December 24, 1926.

The present invention relates to loud speakers of the type disclosed in my copending application, Serial No. 77,033, filed Dec. 22, 1921. The loud speaker disclosed in that application comprises a central relatively light and stiff tympanum, preferably conical in shape, and a surrounding external sound board or resonator having greater mass than that of the central diaphragm. The connection between the central tympanum and the external resonator or sound board is such that the central tympanum will respond to the relatively high frequencies and will efficiently reproduce the high tones or sounds, and the relatively low frequencies will be transmitted through said connection to the sound board so that it will respond to the relatively low frequencies and will efficiently reproduce them. The principal object of this invention is to provide a loud speaker of the foregoing type, the sound board of which is made of balsa wood.

It has been found that a loud speaker of the foregoing type produces superior results if the sound board be made of balsa wood. Balsa wood seems to have the requisite properties to improve considerably the regeneration of the relatively low frequencies which are passed on to the sound board for reproduction. I am not prepared to state exactly what properties of balsa wood are responsible for the improved operation of the loud speaker disclosed in this application, but undoubtedly the soft nature of this type of wood and its extreme lightness are contributing factors.

Several forms of loud speakers in which balsa wood may be advantageously employed are disclosed in the accompanying drawings, in which

Fig. 1 is a front view of a loud speaker especially designed for use in hotels, theatres, concert halls and similar places where a large volume of sound is desired;

Fig. 2 is a side elevation of the speaker shown in Fig. 1;

Fig. 3 is a rear view of the loud speaker shown in Fig. 1;

Fig. 4 is a vertical section taken on the line 4—4 of Fig. 3;

Fig. 5 is an enlarged detail vertical section

of the central portion of the loud speaker showing the connection between the central tympanum and the external sound board;

Fig. 6 is a front elevation of another type of loud speaker operating on the same principle as that shown in Fig. 1;

Fig. 7 is a top plan view of the loud speaker shown in Fig. 6;

Fig. 8 is a rear elevation of the speaker shown in Fig. 6;

Fig. 9 is a vertical section taken on the line 9—9 of Fig. 8.

Referring first to Figs. 1 to 5 inclusive, the loud speaker shown in these figures comprises a central conical tympanum 1 coupled to a vibratory resonator or sound board 2 by means of a semi-flexible coupling, shown in Fig. 5. The conical tympanum 1 is preferably made of cover paper cut and folded to shape and glued along a radial seam. Near the outer edge of the cone thus formed the paper is creased and then folded up to form a forwardly flaring brim 3 (Fig. 5). This brim naturally assumes an angle to the plane of the base equal to the angle between the radial elements of the cone and that base. The outer edge portion of the brim 3 is preferably glued to the inner circular edge of the resonator or sound board 2. For this purpose the inner circular edge of the sound board is tapered as shown at 4 and the outer edge portion of the brim 3 seats upon and is glued to the tapering surface thus formed. In gluing or cementing the brim to the beveled edge 4 it is important that a part of the brim be left free to form a hinge on which the cone may float. Thus with a brim $3\frac{1}{4}$ " wide the cemented portion may have a width of $\frac{1}{4}$ of an inch more or less and the remainder of the brim may be left free to swing.

The resonator or sound board 2 in accordance with this invention is made of balsa wood. It can conveniently be made of 3-ply balsa wood as shown in Fig. 5 with the grain 95 of the inner ply running transverse to the grain of the two outer plies.

The vibratory actuating force is applied to the apex of the conical tympanum by means of a rod or wire 5 which is adapted to be 100

maintained in fixed relation with the diaphragm by means of a set screw 6. The rod 5 may be actuated by electromagnetic mechanism housed in the casing 7. The casing 7 may be attached to a support or spider 8 which in turn may be affixed to the resonator or sound board by means of wood screws 9.

While the loud speaker shown in Figs. 1 to 5 inclusive may be made of any desired size within reasonable limits, it has been found that for concert work excellent results have been obtained by making the conical tympanum approximately 17 inches in outside diameter and the resonator or sound board approximately 4 feet in outside diameter. The relatively large size of the loud speaker shown in Figs. 1 to 5 inclusive makes it desirable to suspend it by cords or chains which may be attached to any suitable part of the loud speaker, preferably the spider 8. The loud speaker may be suspended from the ceiling of a room, a bracket or any other supporting device.

The loud speaker shown in Figs. 6 to 9 inclusive is very similar in construction to that above described as it comprises a conical tympanum 1', a sounding board or resonator 2', a spider 8' for supporting the casing 7' of the electromagnetic actuating mechanism, and a forwardly flaring brim 3' on the cone which is attached to the inner edge of the sound board in the same manner as explained in connection with Figs. 1 to 5. The resonator or sound board 2' of this form of the loud speaker is also made of balsa wood as in the case of the loud speaker described above. The main difference between the speaker shown in Figs. 6 to 9 inclusive and that shown in the first five figures is that the sound board or resonator 2' is of smaller diameter than the sound board shown in the first five figures. The conical tympanum 1' may or may not be smaller than the conical tympanum of the loud speaker of Figures 1 to 5. The reduction in overall size of the loud speaker shown in Figs. 6 to 9 inclusive makes it possible to support the speaker on a table or other horizontal surface and for this reason the sound board 2' is provided with suitable legs or cross pieces 10 glued or otherwise fastened to the sound board. The sound board may be provided with an opening 11 to provide a hand grip for moving the loud speaker from one place to another. In constructing a loud speaker of the type shown in Figs. 6 to 9 I have found that excellent results are obtained by making the cone 2' approximately 15½" in diameter and the sound board approximately 22" in diameter. This makes the transverse width of the annular sound board approximately 3½" but good results may be obtained by making the sound board of even less width than this or of even greater width than the sound board shown in Figs. 1 to 5 inclusive.

In both types of speaker the central conical tympanum efficiently reproduces the higher tones and perhaps some of the intermediate tones while the surrounding annular resonator or sound board efficiently reproduces the lower or bass notes. By reason of the fact that the sound board is made of balsa wood, the reproduction of the lower or bass notes is considerably improved. The lower notes are not only more accurately reproduced but the tonal quality is considerably improved, the reproduction being soft and mellow.

In a loud speaker constructed in accordance with the foregoing description, the regenerated or reproduced sound waves are substantially directly proportional both quantitatively and qualitatively to the actuating force and the sound so reproduced retains substantially the same balance of high and low tones as the original sound from which the actuating force was derived.

In the claims the term "diaphragm" is used to designate the entire vibratory body including the tympanum and the sound board.

I claim:

1. A loud speaker comprising a central relatively light and stiff tympanum, an external balsa wood sound board of greater mass than the diaphragm, and a flexible coupling between the two adapted to permit the central tympanum to respond to relatively high frequencies and adapted to transmit the relatively low frequencies to the sound board.

2. A loud speaker comprising a central conical tympanum, an external balsa wood sound board of greater mass than the tympanum, and a flexible coupling between the two adapted to permit the conical tympanum to respond to relatively high frequencies and adapted to transmit the relatively low frequencies to the sound board.

3. A loud speaker comprising a central conical tympanum, an external balsa wood sound board and a connection between the conical tympanum and the sound board adapted to permit the central tympanum to respond to relatively high frequencies and adapted to transmit the relatively low frequencies to the sound board.

4. A loud speaker comprising a central conical tympanum, a balsa wood sound board extending radially beyond the conical tympanum and a connection between the conical tympanum and the wooden sound board adapted to permit the conical tympanum to respond to relatively high frequencies and adapted to transmit the relatively low frequencies to the wooden sound board.

5. A loud speaker comprising a central conical tympanum having an integral forwardly flaring brim portion, and a balsa wood sound board extending radially beyond

- the conical tympanum, said forwardly flaring brim portion of the conical tympanum being attached to the sound board.
6. A loud speaker comprising a conical tympanum provided with a peripheral corrugation forming a hinge portion, and a balsa wood sound board extending radially beyond the conical tympanum, said hinge portion being secured to said sound board.
10. 7. A loud speaker comprising a balsa wood sound board, and a conical tympanum flexibly connected thereto so that a portion of the sound board extends radially beyond the conical tympanum, the flexible connection between the conical tympanum and the sound board being adapted to permit the conical tympanum to respond to relatively high frequencies and being adapted to transmit the relatively low frequencies to the sound board.
15. 8. A loud speaker comprising a central conical tympanum made of paper, an external sound board made of balsa wood, and a flexible connection between the two adapted to permit the conical tympanum to respond to relatively high frequencies and adapted to transmit the relatively low frequencies to the sound board.
20. 9. A loud speaker comprising a balsa wood sound board having a central opening, a conical tympanum mounted in said opening, actuating means for the conical tympanum and means for supporting said actuating means comprising a support attached to the sound board and spanning the central opening thereof.
25. 10. A loud speaker comprising an annular flat balsa wood sound board having a circular central opening, a conical tympanum having a circular periphery, said conical tympanum being mounted in said opening, and a flexible coupling between the conical tympanum and the sound board adapted to permit the conical tympanum to respond to relatively high frequencies and adapted to transmit relatively low frequencies to the sound board.
30. 11. A loud speaker comprising an annular balsa wood sound board having a central opening the edge portion of which is provided with a tapering seat, and a conical tympanum mounted in said opening, said tympanum having a forwardly flaring frusto-conical brim portion secured to the sound board on said tapering seat.
35. 12. A loud speaker comprising a flat annular sound board made of balsa wood, said sound board having a central opening the edge portion of which is provided with a tapering seat, and a fibrous conical tympanum mounted in said opening and having an integral forwardly projecting brim portion, a part of said brim portion being attached to the sound board at said tapering seat.
40. 13. A loud speaker comprising a diaphragm, and means for applying vibratory energy thereto, the portion of said diaphragm where the energy is applied being of relatively small mass and freely responsive to the higher frequencies, and said diaphragm having another portion of greater mass formed of balsa wood which is freely responsive to the lower frequencies.
45. 14. A loud speaker comprising a diaphragm having a sound reproducing rim of balsa wood which is freely responsive to the lower frequencies and a portion of less mass within said rim which is freely responsive to the higher frequencies, and means for impressing vibratory energy on said portion within the rim.
50. In testimony whereof I affix my signature.
